UNITED STATES PATENT OFFICE.

LEONARD A. MACLEAN, OF READING, MASSACHUSETTS.

MACHINE FOR PATCHING SHIPPING TAGS, ETC.

Application filed October 24, 1927. Serial No. 228,154.

This invention relates to a machine for applying to a body of sheet material, such as a shipping-tag body, the reinforcing patches with which shipping tags are usually provided, the body being provided with a punched hole and the patches being provided also with punched holes, and therefore annular, and applied to opposite sides of the body with their holes registering with the hole in the body, the patches being adhesively secured to the body.

The object of the invention is to provide a simple machine, easily operable by the muscular power of the operator, and suitable for use in job printing offices, in the production of patched or reinforced tags and other articles, when the number required to fill an order is so small as not to warrant the employment of a bulky, complicated and expensive tag machine, such as is usually employed to automatically perform the operation of making patched or reinforced tags.

A particular object of the invention is to provide a patching machine adapted for use with a flexible patch strip which is fed end-wise step by step by a feeding element of the machine, and includes a plurality of patches partially prepared, by the operation of making the strip, for application to a tag or other body, the patches being so nearly completed during the manufacture of the patch strip that they are easily detachable from the strip by the machine, and preparatory to being attached by the machine to tag bodies presented to the machine by the operator.

Of the accompanying drawings forming a part of this specification,—

Figure 1 is a side view, showing elements of a machine embodying the invention, without the patch strips hereinafter described.

Figure 2 is a sectional view, on the plane indicated by line 2—2 of Figure 1.

Figure 3 shows in perspective a portion of one of the patch strips.

Figure 3^a is a view similar to Figure 3, and showing a modification.

Figure 4 shows in perspective a patch detached from a patch strip by the operation of the machine.

Figure 5 is a fragmentary perspective view, showing portions of the machine and portions of two patch strips.

Figures 6 and 7 are fragmentary sectional views on the plane indicated by line 2—2 of Figure 1, showing portions of a tag body and portions of two patch strips, and illustrating

the operation of detaching patches from the strips and applying them to the body.

Figure 8 is a fragmentary perspective view, showing a portion of the tag body and the body conditioning rolls shown by Figure 1.

Figure 9 is a fragmentary perspective view, showing a modification.

Figure 10 is a side view, showing a portion of a tag body.

Figure 11 is a side view of the tag as completed by the machine.

Figure 12 is an enlarged section on line 12—12 of Figure 11.

The same reference characters indicate the same parts in all of the figures.

In the drawings, 15 designates a fixed punching die, and 16 a moveable punching die, said dies being the usual male and female dies, adapted to punch a hole 18 (Figure 12) in the body 17 of a tag, or other article of sheet material, such as a show card, intended to be hung on a stud projecting from a vertical wall. The fixed die 15 is attached to a base 19, forming a part of the frame of the machine, and attached, in this instance, to a bench or table 20. The moveable die 16 is attached to a reciprocating plunger 21, movable in fixed guides 22, constituting parts of the frame. The upper end of the fixed die, and the lower end of the plunger constitute opposed pressing faces, adapted to press the patches hereinafter described against opposite sides of the body 17 the pressing face of the plunger being formed on the lower end of a plunger enlargement 21^a.

23 designates a severing cutter fixed as by a screw 24, to the plunger at one side of the pressing face thereof, and adapted to sever patches from the above-mentioned patch strips, as described later. Between the punching dies is a body-locating pocket 25, best shown by Figure 1, in which a body 17 is insertable by hand. In this instance, the sides of the pocket are formed by fixed spaced-apart plates 26 and 27 (Figure 1). The plate 27 is fixed to supports 29 on the frame and is provided with elongated staple-shaped members 28, constituting, with the plate, an upper guide for one of the patch strips. The plate 26 and another plate 31 spaced therefrom, are fixed to a standard 30 (Figure 1), attached to the base, said plates 110 being connected at opposite edges and constituting a lower guide for the other patch

strip. The several plates are apertured, as shown by Figure 2, to permit the pressing face of the plunger to pass through the plates when the plunger is projected downwardly, 5 as indicated by Figure 7.

32 designates a feed member, which is preferably a roll, fixed to a shaft 33, journaled in bearings in standards 34, fixed to the base, or to the bench 20, and adapted to be rotated 10 step by step by means hereinafter described.

The machine is adapted for use with a patch strip 36, and in preferred embodiment of the invention, with two of said strips, each separably engageable with the feed member 32, and movable step by step thereby in the upper and lower guides above described, the strips constituting a renewable element of the machine. Each strip may be of indeterminate length and is preferably composed of 20 kraft, or other suitably tough paper, from which tag patches are usually made, and is provided with a row of patches 37, partially detached from the strip by substantially circular incisions 38, extending through the 25 thickness of the strip, the ends of the incisions being at opposite sides of a narrow neck 39, connecting the patch with the strip, and adapted to be severed by the plunger knife 23, to form the patch shown by Figure 4. 30 The incisions form the major portions of the margin of the patch, and said margin is completed by the severing action of the knife.

Each patch strip is provided with holes 40, adapted to be engaged by radial pins 41, on 35 the feed member 32, as shown by Figure 5. The machine comprises operating mechanism including means for reciprocating the plunger, and means for moving the feed member step by step, in timed relation with the movements of the plunger to advance the patch strips step by step in their guides, and cause 40 registration of the partially severed patches with the pressing faces so that when the plunger is projected, the cutter 29 severs the 45 necks 39 in the patch strips.

The plunger-reciprocating means includes, in this instance, a spring 42 normally raising or retracting the plunger, a lever 43, fulcrumed at 44 (Figure 1) to an ear on the 50 frame, and bearing on the upper end of the plunger, and a rod 144 connected with one end of the lever and extending downwardly to a treadle (not shown), whereby the rod may be depressed to project the plunger.

55 The means for moving the feed member step by step includes, in this instance, an arm 45 (Figure 2) fixed to the rod 144, a lever 46, fulcrumed at 47 to a fixed ear 48, a rod 49, connecting the lever with the arm 45, a lever 50, fixed to the shaft 33, of the feed member, a link 51, connecting the levers 46 and 50, and a pawl 52, pivoted to the lever 50, and engaging a ratchet 53, fixed to the shaft 33.

60 The step-by-step rotation of the feed member caused by movements of the plunger, is

illustrated by full and dotted lines in Figure 2.

The arrangement is such that when the patch strips 36 are engaged with the feed member 32, holes 40 of the strips receiving pins 41 of the feed member, and a body 17 is inserted in the pocket, the operation of the described mechanism causes the punching of the body 17 by the dies, the severance of strip necks 39 by the cutter 29, and pressure of the severed patches against opposite sides of the body by the pressing faces of the plunger and the fixed die. When the plunger is retracted, the patch strips are advanced one step to bring other patches into position to be 75 detached and pressed against the next body 17 inserted in the pocket.

The patch strips 36 are prepared by mechanism provided for that purpose (not shown herein), including means for cutting the incisions 38 and holes 40, and leaving the necks 39. Said mechanism preferably includes also means for punching holes 55 (Figure 3) in the patch strips, said holes registering with the movable punching die 16, as indicated by Figure 6, so that the duty of cutting the holes in the patches is not imposed on said die, the power required to operate the machine being 80 reduced to a minimum.

I do not limit myself, however, to the patch strips having the holes 55, and may omit said holes, as indicated by Figure 3^a, in which case the die 16 will punch both the patches and the body 17.

Adhesion of the severed patches to the body 100 17 may be caused by any suitable means. The sides of the patch strip contacting with the body, may have dried gum coatings, and the portions of the body 17 with which the patches contact, may be moistened by the operator before the body is inserted in the pocket. To this end the machine may be provided with a pair of moistening rolls 57, one in fixed bearings, and the other spring 105 pressed, the rolls having absorbent surfaces of felt or the like. The operator may apply water from time to time to the rolls. The operator partly inserts the body 17 in the nip of the rolls and then withdraws it before inserting it in the pocket, thereby moistening 110 the portions of the sides of the body with which the gummed patches subsequently contact.

If desired, a liquid adhesive may be similarly applied to the rolls and by the rolls to the body 17, the gum coatings of the patch strips being omitted. As shown by Figure 9, the plunger cutter 29 may be reduced in length, so that it will sever only the necks 39 of the upper patch strip, and the fixed die 15 may be provided with an upwardly facing cutter 29^a adapted to sever only the necks 39 of the lower patch strip.

It is obvious that if only one patch is desired on each body 17, one of the patch strips

may be omitted, hence I do not limit myself to the conjoint use of two carrying strips, although this is preferable, especially in a tag machine.

5 The plunger enlargement 21^a is provided with a stripper 60, which is movable relative to the enlargement and is pressed downward by a spring 61, as shown by Figures 1, 2 and 6, when the plunger is raised, the stripper bearing 10 on the lower end of the enlargement when the plunger is projected, as shown by Figure 7. When the plunger rises the stripper is forced downward by its spring and strips a tag and its patches from the die 16. The 15 stripper is a flat annular plate surrounding the die 16, and constitutes the pressing face of the plunger, when the latter is in the position shown by Figure 7.

The patch strip herein described is claimed 20 in my divisional application entitled Patch strips for a tag-patching machine, filed May 5, 1928, Serial No. 275,382.

I claim:

25 A patching machine comprising in combination, a pair of punching dies, one fixed and the other movable, adapted to cut a hole in a body of sheet material, a reciprocating plunger guided in a predetermined path and carrying the movable die, said fixed die and

plunger having opposed pressing faces, a 30 body-locating pocket between the dies, strip guiding means beside the pocket including an upper guide located at one side of the pocket and adapted to guide an upper patch strip and a lower guide located at the opposite side 35 of the pocket and adapted to guide a lower patch strip, a feed member for engaging flexible patch strips, and operating mechanism including means for reciprocating the plunger, and means for moving the feed 40 member step by step, in timed relation with the movements of the plunger, to advance the patch strips step by step in the guiding means and cause registration of a patch in each strip with the punching dies, the arrangement 45 being such that when the patch strips are engaged with the feed means and inserted in the guiding means and a body is inserted in the pocket said mechanism causes the punching of the body by the dies, the separation 50 of a patch from each patch strip and pressure of the separated patches against the body by the pressing faces, means being provided for causing the separated patches to adhere to the body.

In testimony whereof I have affixed my signature.

LEONARD A. MACLEAN.
